UNITED STATES PATENT OFFICE.

JOHAN GUSTAF ENSTRÖM, OF GOTENBORG, SWEDEN.

SEAL-LOCK FOR BOXES.

1,324,111.

Specification of Letters Patent. Patented Dec. 9, 1919.

Application filed August 16, 1918. Serial No. 250,201.

To all whom it may concern:

Be it known that I, JOHAN GUSTAF ENSTRÖM, a subject of the King of Sweden, residing at Nordensköldsgatan 28, Gottenborg, in the county of Gottenborg and Bohus and Kingdom of Sweden, have invented new and useful Improvements in Seal-Locks for Boxes, of which the following is a specification.

10 This invention refers to boxes or cases which are used for shipping or other transporting purposes. The main object of this invention is to provide a box or case, which is exceedingly safe and reliable, so that unauthorized persons cannot get at the contents of the same either through the cover proper or through the sides or bottom without such tampering being known.

15 A further object of the invention is to provide a box or case of an extremely strong and durable design, so that it can be reused a number of times without being spoiled by repeated spiking or nailing.

20 A further object of the invention is to provide a shipping box or case, that can be transported in a closed and sealed condition without need of a special key, so that the receiver may be able to uncover the box by means of the locking device proper and nevertheless be sure, that the box has not been uncovered during the transport by any unauthorized person.

25 The improved box or case comprises a specially designed locking device, provided to be officially closed and sealed without need of a special key, as well as specially designed mountings for keeping the sides, bottoms and covers rigidly and detachably secured together without use of spikes, 30 nails, screws or similar temporary applied means.

35 In the accompanying drawings:

Figure 1 represents an elevation frontal view of the locking device in a closed stage, 40 Fig. 2 a similar view, but partly in section and with the locking device ready to be withdrawn,

Fig. 3 the same view as in Fig. 1, but with the locking bolt removed,

45 Fig. 4 the locking bolt proper,

Fig. 5 a cross section through the locking device on the line V—V in Fig. 1,

Fig. 6 a similar cross section on line VI—VI in Fig. 1,

Fig. 7 a similar cross section on line 55 VII—VII in Fig. 1,

Fig. 8 a similar cross section on line VIII—VIII in Fig. 1,

Fig. 9 a sectional view of the box with the cover partly opened up, 60

Fig. 10 a sectional view with the cover closed and the locking device sealed,

Fig. 11 a frontal view of the locking device when sealed,

Fig. 12 a similar view with the locking 65 device sealed and closed by a cover.

In the drawings the sides of the box or case are marked with the reference figures 26 and 260 and the cover with 27. The cover is on its inner surface provided with 70 mountings 47, adapted to coöperate with iron lugs 46, fastened on the sides 26, so that when the cover is pushed to the left from the position shown in Fig. 9, the cover will be locked upon the box, as shown in Fig. 10. 75 In the first mentioned figure, the cover 27 is moved to the right, so that the mountings 47 are not engaged with the lugs 46, and the cover can be removed from the box, and in Fig. 10 the cover has been pushed to the 80 left and thereby the mountings 47 to coöperate with the lugs 46, so that the cover cannot be raised. Similar mountings 47 and lugs 46 are provided on all the sides as well as on the bottom 126 of the box, as shown 85 in Figs. 9 and 10, with the only difference, that the mountings 47 are fastened in opposite directions on opposite sides, thus preventing separation of the sides and bottoms from one another without unscrewing the 90 mountings from the corresponding parts.

On the front side 260 there is mounted a casing 1, and the cover 27 is provided on the inner surface near the front side 260 with an iron plate 24 with prongs 25 with 95 hooked ends 30, which prongs are fitted to pass through holes in the top side of the casing 1. Bars 43 are fastened to the front side 260 on its inner surface and are provided with prongs 28 with hooked ends 29 100 fitted to pass through holes in the bottom side of the casing 1. The last mentioned prongs 28 retain the casing 1 in place on the front side 260.

Into the casing 1 there are two members 31 each provided with two opposed hooked ends or projections 34 leaving a free space 134 between the members 31. Into said spaces 134 there is interposed a member 32 serving as a lock bolt, which member is provided with rather narrow end portions 33, suited to fit the free spaces 134, with an intermediate portion of a larger width provided with an aperture 36. The two end portions 33 are provided each with lugs 35 of a larger width than the gap 131 between the opposing ends 34 of one and the same member 31, so that, when the member 32 is moved to the left, as illustrated in Fig. 1, with the lugs 35 positioned in the spaces 134, the hooked ends 34 prevent the member 32 from being removed laterally out of the casing. The narrow end portions 33 are of somewhat less width than the spaces 131, so that the member 32 can be laterally introduced into or withdrawn from the spaces 134, when moved to the right as shown in Fig. 2. When in place in the spaces 134, either in the right hand end position as in Fig. 2 or in the left hand end position as in Fig. 1, the end portions 33 engage the hooked ends 34 on their upper side and the hooked ends 30 on their down side, so that the cover 27 cannot be raised from its position on the top edges of the sides 26, 260. As soon as the member 32 is moved to the left as in Fig. 1 with the cover 27 in the closed position according to Fig. 10, the lugs 35 coöperate with the hooked ends 34 and prevent the cover 27 from being released from the lugs 46 by moving laterally to the right, as shown in Fig. 9. Thus the cover 27 will be securely kept in place on the box, when the locking bolt member 32 is in its proper position according to Fig. 1.

The casing 1 further is provided with an interior cover 12 hinged on pins 121 and provided with lug 20, which, when such cover is closed, as in Fig. 5, coöperates with the aperture 36 in the member 32, when this is in the right hand, locking position as in Fig. 1 and acts to retain said member 32 in this position. This position will be maintained irrespective of the rough handling to which a box is usually subjected during transit, because the border 37 of the aperture 36 coöperates with the said prong 20.

In the projecting ends 34 there are provided holes 44, through which a cord 45 can be thrust and sealed by a lead or seal 150, so that the cord 45 cannot be removed without breaking the seal, and consequently any unauthorized entrance into the box will be detected. For this purpose the holes 44 are made so near the outer ends of the projections 34, that they are to be found on the outside of the cover 12, when the latter is closed, and accordingly said cover cannot be

opened and the locking bolt member 32 reached without first removing the seal 150.

An outer cover 13 closes the casing 1 and protects the seal 150 from unintentional damage. The outer cover 13 is provided with a tongue 38 with a hole 39, which registers with a hole in a tongue 40 on the casing 1, when the cover 13 is closed, and through these two coöperating holes there can be thrust a small wire 41 twisted to a loop, in order to retain the outer cover in closed position.

I do not limit myself to the special arrangement herein shown wherein the casing 1 is attached to the box side 260 and the coöperating parts in the cover 27, but I desire to protect also the natural modification of placing the casing 1 in the cover 27 and the coöperating parts in the box side, as this modification will bring about the same result, though it may be deemed as somewhat less practical in ordinary use.

Having thus described my said invention and how it is to be performed, what I claim as new and desire to protect by Letters Patent is:

1. A lock of the class described comprising, in combination, with a box and its cover, a casing on the box, members on the cover and extending into the casing, and means within the casing for locking the members within the casing against lateral displacement.

2. A lock as embodied in claim 1, said means comprising a slidable member and means for locking said member against movement.

3. A lock as embodied in claim 2, said locking means being hinged and movable at right angles to said members.

4. A lock of the class described comprising, in combination with a box and its cover, a casing on the box, hooked members on the cover and extending into the casing, hook members in said casing reversely disposed with relation to the members on the cover and coacting therewith to form a guide-way, a locking bolt movable in said guide-way, said bolt being insertible laterally in said casing and capable of occupying a releasing and a locking position, and means in the casing for locking said bolt against lateral displacement when in the locking position.

5. A lock as embodied in claim 4, and prongs formed on the bolt, said means comprising projections which coact with said prongs.

6. A lock as embodied in claim 4 and means for locking the sliding bolt in the locking position.

7. A lock of the class described comprising, in combination, with a box and its cover, a casing on the box, members on the cover and extending into the casing, a slid-

able member within the casing for locking the members against lateral displacement, means for locking said slidable member against movement, removable means for locking the last mentioned means, and a seal for the removable means to prevent removal thereof without detection.

In testimony whereof I have affixed my signature in presence of two witnesses.

JOHAN GUSTAF ENSTRÖM.
